MAGAZINE LUBRICATING SYSTEM

Filed June 1, 1925

INVENTOR
CORNELIUS T. MYERS

BY
A. D. T. Libby
ATTORNEY

UNITED STATES PATENT OFFICE.

CORNELIUS T. MYERS, OF AVENEL, NEW JERSEY.

MAGAZINE LUBRICATING SYSTEM.

Application filed June 1, 1925. Serial No. 34,015.

This invention relates to means for lubricating bearings of various kinds and is particularly adapted for use in connection with automotive vehicles.

- 5 In my Patent 1,620,277 issued March 8, 1927, I have set forth the advantages of oil lubrication for the chassis of automotive vehicles and have pointed out in said application how the oil, which is drained from the 10 crank case of the vehicle may be utilized in various magazines or reservoirs distributed at different parts of the vehicle for lubricating the surfaces closely adjacent said magazines.
- 15 It is the object of my present invention to provide an improvement on said patent as well as on the arrangement disclosed in my Patents 1,314,689 issued September 2, 1919, and 1,387,295 issued August 9, 1921.
- 20 In the above mentioned patents, I have disclosed individual, or, local magazines or reservoirs for containing oil with means within said magazines for feeding oil to the surfaces to be lubricated. In each case, the 25 individual magazines are provided with caps or filling means by which oil may be put into the magazines. In ordinary practise I have found that these magazines need filling only three or four times a year, but, in order to 30 eliminate even this amount of work and to insure that the local magazines are continuously provided with oil, I have, in my present case, provided a common, or, central reservoir of suitable size which may be filled 35 with new oil, or as mentioned in my Patent 1,620,277, with the oil drained or taken from the engine crank case, it being the well established practise to drain the oil from the engine crank case at stated intervals and re- 40 new with fresh oil. It has been found that in practically all cases, there is still a large amount of lubricating qualities still left in oil taken from the engine crank case, and instead of throwing this away, I propose 45 to use it for lubricating the parts of the chassis.
- My present improvement will best be understood by reference to the drawing, in which,
- 50 Figure 1 illustrates one side of the front end of a vehicle chassis showing the common

reservoir and a pair of local magazines at the front spring shackles.

Figure 2 is an enlarged view of one of the local reservoirs shown in Fig. 1.

Figure 3 shows a local magazine for attachment to a member having a surface to be lubricated, substantially the same as illustrated in my copending application, Serial No. 9,727 filed February 17, 1925.

Figure 4 is a fragmentary view showing the front end of an automotive vehicle illustrating means for filling the common or central reservoir from the engine crank case.

In the various figures wherein like numbers refer to corresponding parts in the various views, 1 is a side member of a chassis of an automotive vehicle; 2 is an axle on which is carried the usual spring 3. To the member 1 is attached a plate 4 carrying an oil magazine 5 having a cap screw 6, which, according to the disclosure of my Patent 1,314,689 already referred to, was for the purpose of filling the magazine, but in the present case, it is used only for inserting the wick 7 carried in tube 8 leading to a spring bolt carried in a hole 9. In the present case, oil is fed to the local magazine 5 from a common or central reservoir 10 which may be mounted in any satisfactory place on the vehicle, but preferably above the level of the highest local magazine so that oil may feed by gravity through the pipes 11 to the local magazines 5. As shown in Fig. 2, the pipe 11 extends into the magazine 5 for some distance, and since the oil chamber of the magazine 5 is made air tight above the oil level, the oil level therein will be maintained at the same level such as 12. As the oil in each individual magazine 5 is used up by being fed through the wick 7, additional oil is supplied from the common reservoir 10 in a manner well understood.

It is to be further understood that while I have shown in Fig. 1, only two local magazines 5, there is a number of these at various parts of the vehicle requiring lubrication and that the system of piping from the reservoir 10 may be of any satisfactory kind, although, the pipes used should be of a size as to insure a non-obstructive flow between the common reservoir 10 and the local magazines 5. By

using a suitable size pipe for this purpose, same is not readily subjected to damage or stoppage such as is apt to be the case if a relatively small diameter pipe is utilized.

5 The magazine shown in Fig. 3 is one that is adapted to be constructed separately from the other parts and attached by means of a screw threaded member 13, to the member 14, carried by the support members 15 and 10 16 which may be any members such as spring shackles. In this case the magazine 5 is attached to the member 14 by passing the member 13 through an opening closed by a cap 17 all as disclosed in my application 15 Serial No. 9,727 hereto referred to.

The common reservoir 10 is preferably of a size sufficient to contain oil enough to maintain a supply to the local magazines for a considerable period of time.

20 In Fig. 4 I have shown a pump 18 having a suction line 19 running to the sump 20 of the crank case of the engine 21. From the pump 18 a discharge line 22 extends to the common reservoir 10 which is preferably 25 provided with an over-flow pipe 23 carrying the surplus oil back to the engine crank case. As shown in Fig. 4 the pump 18 has a manual type of control for pumping the oil from the engine crank case to the reservoir 10. In this arrangement, the reservoir 10 is preferably provided with a visual indicator 24 to indicate to the operator the level 25 of the oil in the reservoir 10. It is obvious that a pump operated by the engine 30 or moving part of the vehicle may be used either continuously or intermittently, but, since the consumption of oil in my present system of lubrication is economical, I find that it is desirable to use only the intermittent arrangement. It is to be understood 40 that the pipe 19 so connects with the sump 20 of the engine that there will always be some oil left in the engine crank case for lubrication of the engine, which, is usually 45 provided with its own indicating gauge to show the amount of oil in the engine.

It is to be remembered that while the oil taken from the engine crank case may have, and usually does have, certain solid impurities in it, the wicks 7 act as filters so that only the lubricating oil is carried to the surfaces to be lubricated.

It is to be understood that the main reservoir and magazines may be provided with 55 drain plugs so that they may be cleaned out whenever necessary. With this system of lubrication, it will be seen that a considerable quantity of oil is carried at each local magazine and that these magazines are automatically replenished with oil from the common reservoir according to the needs of each, without any reference to any of the other magazines. This system thus provides a large reserve of lubricant in the local magazines even should the supply in the main

reservoir become exhausted, and, as has been pointed out, the supply of lubricant in the local magazines is sufficient to last many weeks, or, even months. It is also within the scope of this invention to fill the local magazines by means of a piping system through which oil may be forced from time to time by means of a pump attached to some source of lubricant supply as the alternative for the gravity feed shown in Fig. 4. It is obvious 75 that a cut-off valve may be placed in the main feed line 11 from the common reservoir 10 so that the supply of oil to the various magazines may be cut off completely if desired. 80

While I have disclosed in a more or less diagrammatic manner the way in which my invention may be put into practise, it should be clearly understood that the details may be varied over a considerable range without departing from the spirit of my invention or the scope of the appended claims. 85

Having thus described my invention what I claim is:

1. In a magazine lubricating system, a plurality of magazines located closely adjacent a surface to be lubricated, said magazines being adapted to hold a considerable quantity of lubricant, a wick within each magazine for continuously feeding lubricant 90 to the surface to be lubricated and a common reservoir having a pipe connection to each of said plurality of magazines, the pipe extending into its magazine below the normal level of lubricant therein, the magazine being air tight above its normal lubricant level except at the lubricant outlet, thereby automatically maintaining substantially a predetermined quantity of lubricant 95 in each of said magazines so long as there is lubricant in the common reservoir. 100

2. In a magazine lubricating system, a plurality of magazines each located closely adjacent a surface to be lubricated, said magazines being adapted to hold a considerable quantity of lubricant and a common reservoir having a gravity feed to each of said plurality of magazines, said latter magazines being constructed air tight above the normal lubricant level therein except at the lubricant outlet, and connected from a point below the normal lubricant level in the magazine to the common reservoir so the feed of lubricant thereto is controlled by the requirements of each surface lubricated, and a wick in each magazine extending from the lubricant therein to the surface to be lubricated, that portion of the wick in the magazine as it enters a passageway leading from the magazine, being out of the body of lubricant. 115 120

3. In a magazine lubricating system, a plurality of magazines each located closely adjacent a surface to be lubricated, said magazines being adapted to hold a consider- 125 130

- able quantity of lubricant, said magazine being air tight above the normal lubricant level, except at the lubricant outlet, means within each of said plurality of magazines 5 having a part extending above the normal level of lubricant within the magazine for filtering and continuously feeding lubricant to the surface to be lubricated and a common reservoir for directly charging automatically through unobstructed pipes each 10 of said plurality of magazines according to its individual requirements, said pipes terminating in the magazines below the normal level of lubricant therein.
- 15 4. In a magazine lubricating system for an automotive vehicle having a prime mover, a plurality of local oil magazines distributed at various parts of the vehicle to be lubricated, said magazine being air tight above the normal lubricant level, except at the lubricant outlet, means within the local magazines having a part extending above the normal level of lubricant within the magazine to continuously feed the oil to 20 the local surface to be lubricated, a common reservoir for holding oil for all of said plurality of magazines, pipes directly connected between the common reservoir and the local magazines, said pipes terminating 25 below the normal lubricant level within the magazines and establishing an air pressure within said local magazines so the same are automatically refilled as the oil is used therefrom, a source of oil and means for charging 30 said common reservoir from said source.
5. In a magazine lubricating system for an automotive vehicle having a prime mover, a plurality of local oil magazines located closely adjacent to the various parts of the vehicle to be lubricated, said magazine being air tight above the normal lubricant level, except at the lubricant outlet, means within the local magazines to directly and continuously feed the oil to the local 40 surface to be lubricated, a common reservoir for holding oil for all of said plurality of magazines, pipes directly connected between the common reservoir and the local magazines, said pipes terminating below the 45 normal lubricant level within the magazines and establishing an air pressure within said local magazines so the same are automatically refilled as the oil is used therefrom, a source of oil and a pump for moving the oil from 50 said source to said common reservoir, said lubricant feeding means on its way out of the magazine, having a part extending into the air space above the lubricant.
6. In a magazine lubricating system for 55 an automotive vehicle having a prime mover, a plurality of local oil magazines located closely adjacent to the various parts of the vehicle to be lubricated, means within the local magazines to directly and continuously 60 feed the oil to the local surface to be lubri- cated, a common reservoir for holding oil for all of said plurality of magazines, pipes directly connected between the common reservoir and the local magazines cooperating with said local magazines so the same 70 are automatically refilled as the oil is used therefrom, a pump having a suction line to an oil sump in the crank case of the prime mover and a discharge line to said common reservoir and means for taking care of any 75 excess oil pumped into said common reservoir.
7. In a magazine lubricating system for an automotive vehicle having a prime mover, a plurality of local oil magazines located 80 closely adjacent to the various parts of the vehicle to be lubricated, a common reservoir for holding oil for all of said plurality of magazines, unobstructed pipes connected between the common reservoir and the local 85 magazines and cooperating with said local magazines so the same are automatically refilled as the oil is used therefrom, a pump having a suction line to an oil sump in the crank case of the prime mover and a discharge line to said common reservoir, an over-flow pipe between the common reservoir and the engine crank case and wicks in the local magazines to filter and continuously feed the oil to the local surface to be 90 lubricated.
8. In a magazine lubricating system for an automotive vehicle chassis carrying an engine, means for utilizing the engine oil for lubricating the chassis, comprising; a 95 common reservoir, a pump for moving the oil from the engine crank case to said reservoir, means for returning to the engine crank case the surplus oil moved to said reservoir, local oil magazines located closely 100 adjacent to the parts on the chassis to be lubricated, pipes directly connecting the local magazines with said common reservoir and means within the local oil magazines for filtering and feeding the oil therein to the 105 local surfaces to be lubricated.
9. In a magazine lubricating system, a plurality of magazines each individually located closely adjacent a surface to be lubricated, said magazines being adapted to hold 110 a considerable quantity of lubricant, said magazine being air tight above the normal lubricant level, a source of lubricant connected to each local magazine below the normal level of lubricant therein, means including unobstructed pipes for passing the lubricant from said source directly to said magazines, and means within each local magazine extending above the body of lubricant in the magazine into the air space 115 for feeding the lubricant directly to the surface to be lubricated.
10. In a magazine lubricating system for an automotive vehicle chassis carrying an engine, means for utilizing the engine oil 120 125

for lubricating the chassis, comprising; a
pump, local oil magazines located closely
adjacent to the parts on the chassis to be
lubricated, pipes directly connecting the
local oil magazines with the pump and
with a part containing oil being used in
lubricating the engine, said pump being
adapted to transfer the oil from said part

to said magazines and means within said
magazines extending above the normal level 10
of oil in the magazine for filtering and
feeding the oil to the local surfaces to be
lubricated.

In testimony whereof, I affix my signature.

CORNELIUS T. MYERS.
